UNITED STATES PATENT OFFICE.

DEANE D. LENNER, OF AKRON, OHIO.

WASHBOARD.

Application filed June 7, 1922. Serial No. 566,504.

To all whom it may concern:

Be it known that I, DEANE D. LENNER, a citizen of the United States, residing at Akron, in the county of Summit and State of Ohio, have invented certain new and useful Improvements in Washboards, of which the following is a specification.

The present invention relates in general to laundry appliances, and more particularly 10 to a washboard which is provided with a rubbing body formed of some resilient material, such as rubber.

Among the objects of the invention is to provide a resilient rubbing body for washboards which presents a rubbing surface adapted to act in a most effective manner upon the clothes for loosening and removing the dirt with a minimum amount of wear and tear upon the clothes, which can 20 be firmly anchored or secured in position in the washboard frame so that it is not liable to come out of place when in use, and which also embodies novel features of construction, whereby all possibility of water or 25 soap suds getting under the rubbing body and causing the same to bulge is avoided.

Washboards are usually constructed with metal rubbing surfaces, although these are objectionable because of the fact that the 30 metal quickly corrodes or rusts, with the result that jagged edges are often presented unexpectedly and the clothes torn or damaged by catching thereon, or the hands of the operator cut or injured by coming 35 into contact therewith. To a certain extent washboards have also been made with glass rubbing bodies, although these are open to the objection that glass is a brittle material, which is easily chipped and which is 40 completely broken or shattered by a fall. A rubbing body formed of some resilient material, such as rubber does not have these objectionable features. The clothes are readily cleansed without any undue wear 45 and tear thereon, there is no possibility of sharp and jagged edges being unexpectedly presented, and at the same time the rubbing body is of a durable character and comparatively inexpensive to produce.

For illustrative purposes one particular embodiment of the invention will be shown and described in detail, although it must be understood that many modifications and changes can be made in the details of con-

struction, without departing from the spirit 55 of the invention.

For a full understanding of the invention, reference is to be had to the following description and accompanying drawings, in which:

Figure 1 is a perspective view of a washboard constructed in accordance with the invention.

Figure 2 is a longitudinal sectional view 65 through the same.

Figure 3 is a rear view of a portion of the rubbing body.

Figure 4 is a transverse sectional view 70 through a portion of the rubbing body, taken on the line 4—4 of Fig. 3.

Figure 5 is a transverse sectional view 75 through one side of the washboard, taken on the line 5—5 of Fig. 2.

Corresponding and like parts are referred to in the following description, and indicated on all of the views of the drawings by like reference characters.

In carrying out the invention I contemplate the use of some standard construction of washboard frame, such as that illustrated 80 on the drawings. This frame comprises the usual side pieces 1, which are connected at their upper ends by a top 2, and at a point spaced from their lower ends by a cross bar 3. The portions of the side pieces which extend downwardly below the cross bar 3 provide the usual legs upon which the washboard is supported when in use. The rubbing body 4 is mounted upon the washboard frame, and positioned between the lower cross bar 3 and an upper cross bar 5 which forms the soap rest. Each of the side pieces 1 has the inner face thereof suitably recessed at 6 to receive the ends of the cross bars 3 and 5. These recesses 6 are 85 connected by a groove 7 which receives the sides of the rubbing body, and a groove 8 extends upwardly from the upper recess 6 for the reception of the brand board 9. The top 2 is connected by suitable and conventional joints 10 to the upper ends of the side pieces 1, both the top and the upper cross bar 5 being provided with grooves 100 which correspond to the groove 8 of the side pieces and which receive the corresponding edges of the brand board 9. It may also be noted that the upper cross bar 5 is provided with a series of diagonally dis-

posed drain openings 11 which will discharge any water or soap suds which might accumulate in the soap receiving pocket at the top of the washboard upon the front of 5 the rubbing body.

The rubbing body 4 is formed of some resilient material such as rubber. This rubber body may have a reinforcement 12 of fabric or other suitable material, and the 10 outer surface of the rubbing body is roughened so that it will act upon the clothes in the proper manner to loosen and remove the dirt therefrom. The rubbing surface is shown as comprising a series of transversely 15 extending ribs or serrations 13, and these ribs preferably have a substantially V shaped cross section so that they present comparatively sharp edges to the clothes. This form of rubbing surface operates in a very efficient manner, and owing to the resiliency 20 of the material there is no danger of injuring the clothes or cutting the hands of the operator.

The rubbing body, being formed of resili- 25 ent material, is of a flexible character, and it is accordingly important that it be firmly secured to the frame and anchored in position therein, so that there will be no liability of the rubbing element working loose 30 and coming out of place while the washboard is in use. With this consideration in mind, the rubbing body is formed with a rearwardly extending marginal flange 14, which extends completely around the bottom 35 or back board 15 which supports the rubbing body. This back board may be formed in three or more sections, as illustrated, the sections thereof extending transversely between the side pieces 1 and connecting the 40 latter. The grooved portions 7 of the side pieces are sufficiently deep to receive the marginal flanges 14 of the rubbing body, and enable the ends of the bottom boards to obtain a bearing therein. It will also be noted 45 that the cross bars 3 and 5 are suitably channeled at 16 to receive the upper and lower edges of the rubbing body, said channeled portions being also sufficiently deep to receive the corresponding edges of the back board 15. The sides and ends of the rubbing body 4 are thus all received within grooved 50 portions of the washboard frame, and the marginal flange 15 is arranged to interlock with the frame members and back board, so 55 that the rubbing body is firmly anchored in position. The arrangement may be such that when the parts are assembled the mar-

ginal flange will be gripped and slightly compressed by the members between which it is interposed. Not only does this flange 60 result in enabling the rubbing body to be firmly secured to the frame or anchored in position thereon, but it also renders it practically impossible for any water or soap suds 65 to run down and enter the space between the rubbing element and back board in such a manner as to cause an objectionable bulging of portions of the rubbing body.

The washboard frame is of a standard or conventional type, and no claim to novelty 70 is based upon the frame itself. By the present invention a rubbing body of rubber or of some resilient composition of an equivalent nature is adapted to be applied to the standard washboard frame and firmly secured or anchored in position therein, so that there will be no danger of the rubbing body becoming loose and dropping out of position when the washboard is in use. This resilient rubbing body produces a wash- 75 board of highly increased efficiency, which can be manufactured at a comparatively small cost, which is long-lived in its usefulness, and which is at the same time of a clean and sanitary character. 80

Having thus described my invention, what I claim as new and desire to secure by Letters Patent is:

In a washboard of the character described, the combination with a frame of a standard type comprising side pieces and upper and lower cross bars connected to said side pieces, the side pieces and cross bars being provided with grooves to receive a rubbing body, a resilient rubber rubbing body formed with marginal edge flanges projecting rearwardly therefrom, and a backboard disposed between the side pieces and cross bars and having its edges seated on the said side pieces so as to support said rubbing body, edge portions of the backboard being engaged with the said rearwardly projecting marginal flanges of the rubbing body so that the flanges lie beyond the edges and are secured thereby in the grooves, the said edges of the backboard forming abutments engaging with the flanges and cooperating with the walls of the grooves to prevent displacement or shifting of the rubber rubbing body relative to the backboard and said side pieces and cross bars. 100

In testimony whereof I affix my signature.

DEANE D. LENNER.
